US0D1074713S

(12) **United States Design Patent** (10) **Patent No.:** **US D1,074,713 S**
Adams et al. (45) **Date of Patent:** **** May 13, 2025**

(54) **DISPLAY SCREEN OR PORTION THEREOF WITH GRAPHICAL USER INTERFACE**

(71) Applicant: **Canva Pty Ltd**, Surry Hills (AU)

(72) Inventors: **Cameron Adams**, Sydney (AU); **Jess Ruyter**, Newcastle (AU); **Jacob Thomas Grainger**, Sydney (AU); **Marc-Antoine Roy**, Sydney (AU)

(73) Assignee: **Canva Pty Ltd**, Surry Hills (AU)

(**) Term: **15 Years**

(21) Appl. No.: **29/911,723**

(22) Filed: **Sep. 7, 2023**

Related U.S. Application Data

(63) Continuation of application No. 29/782,227, filed on May 5, 2021, now Pat. No. Des. 1,002,665.

(51) **LOC (15) Cl.** **14-04**

(57) **CLAIM**

The ornamental design for a display screen or portion thereof with graphical user interface, as shown and described.

DESCRIPTION

The sole FIGURE is a front view of a display screen or portion thereof with graphical user interface showing of our new design.

The dashed broken lines illustrate text, icons, or the remainder of the graphical user interface and form no part of the claimed design. The dashed-dotted broken lines depict a boundary line of a display screen or portion thereof, and form no part of the claimed design.
